UNITED STATES PATENT OFFICE

141,136

DESIGN FOR A GAME COUNTER RECEPTACLE

Donald B. Alexander, Chicago, and Stephen E.
Toussaint, Glen Ellyn, Ill.

Application February 14, 1945, Serial No. 117,950

Term of patent 14 years

(Cl. D34—5)

To all whom it may concern:

Be it known that we, Donald B. Alexander, residing in the county of Cook and State of Illinois, and Stephen E. Toussaint, residing in the county of Du Page and State of Illinois, have invented a new, original, and ornamental Design for a Game Counter Receptacle, of which the following is a specification, reference being had to the accompanying drawing forming a part thereof.

In the drawing,

Fig. 1, showing our new design, is a top view of the game counter receptacle;

Fig. 2 is a direct side elevational view thereof; and

Fig. 3 is a side elevational view from a corner of the game counter receptacle shown in Fig. 1.

We claim:

The ornamental design for a game counter receptacle, as shown.

DONALD B. ALEXANDER.
STEPHEN E. TOUSSAINT.
